VEHICLE BUMPER GUARD

Frank J. Faulhaber, New York, N. Y.

Application May 7, 1956, Serial No. 41,375

Term of patent 14 years

(Cl. D14—18)

FIG.1

FIG.2

FIG.3

FIG.4

Figure 1 is a view in front elevation of a vehicle bumper guard showing my new design.

Figure 2 is a top plan view of the bumper guard shown in Figure 1.

Figure 3 is a side elevational view taken from the right of Figure 1; and

Figure 4 is a side elevational view taken from the right of Figure 1, but in open position with portions broken away for convenience of illustration.

I claim:

The ornamental design for a vehicle bumper guard, substantially as shown and described.
